UNITED STATES PATENT OFFICE.

ELIE W. LABOMBARDE, OF NASHUA, NEW HAMPSHIRE.

REINFORCED PAPER VESSEL.

Application filed September 2, 1921. Serial No. 497,886.

To all whom it may concern:

Be it known that I, ELIE W. LABOMBARDE, a citizen of the United States, and resident of Nashua, in the county of Hillsborough 5 and State of New Hampshire, have invented certain new and useful Improvements in Reinforced Paper Vessels, of which the following is a specification.

This invention relates to paper vessels or 10 boxes to contain liquids such as milk, or partly liquid substances such as oysters and pickles, and has particular reference to vessels made from flat blanks which, when folded, form vessels which are angular in 15 cross section and, consequently, have corners which are difficult to so form and secure as to be leak-tight.

One of the objects of the invention is to provide liquid containers economically made 20 from flat blanks having patches so located thereon that when the blanks are folded to form receptacles, the corners, especially at the bottom of the receptacle, are so reinforced as to effectually resist the tendency of 25 liquid to force openings at said corners. Preferably the patches are so located and secured that when the blanks are folded to receptacle or container form the patches are doubled or overfolded upon themselves and 30 form packing or caulking at the corner joints.

Another object of the invention is to provide an improved paper receptacle for liquids having an integral portion to serve 35 as a spout when the receptacle is being emptied.

Another object is to provide an improved receptacle for liquids having a top closable portion which will not cause a splashing of 40 the liquid when the filled receptacle is being closed.

With these and other objects in view, the invention consists in the improvements which I shall now proceed to describe and claim.

45 Of the accompanying drawings:

Figure 1 is a plan view of a blank with its corner reinforcing patches, the blank illustrated being one of many forms or types which may be employed in carrying out the 50 reinforcing feature of my invention.

Figure 2 is a perspective view of the blank folded to receptacle form, a portion being broken out to show one of the caulked corners.

55 Figures 3 and 4 are sectional perspective views illustrating how the patches automat-

ically double or over-fold as the blank is folded, the area of the blank shown in said figures being that within the dotted area in Figure 1. It is to be understood that all of 60 the patches double or over-fold in substantially the same way when the blank is converted to receptacle or box form.

Figure 5 is a perspective view of the receptacle as it appears when in condition for 65 pouring liquid therefrom.

The particular form of blank illustrated in Figure 1 is cut and creased to form a bottom section 12 with flaps 13, 13, two wall portions 14, 15, one having side flaps 16 70 and the other having side flaps 17. The wall section 14 has an end flap 18 with an extension 19, and the wall section 15 has an end flap 20. The flaps 17 have extension flaps 21 which serve as part of the closure 75 of the receptacle, and the flap 18 has two side wings 22.

When this form of blank is folded and closed as shown in Figure 2, the receptacle or box has eight corners. In carrying out 80 my present invention each portion of the blank which is to form a corner of the box where leakage might occur has a patch α secured to it. Each of the patches is secured to that surface of the blank which is inside when folded up. The patches for the bottom corners may be divided or continuous as shown in Figure 1.

The patches α are preferably of strong 90 bleached kraft paper. They are adhesively secured to the paper board blank before the blank is waxed or otherwise so treated as to prevent them from being sufficiently held in place during folding to automatically double over as presently described. It is 95 not necessary that the patches be firmly secured. In fact it is preferable that the adhesion shall be of a nature which will hold the patches in place on the blank but will enable portions of the patches to pull away when over-folded as shown in Figures 3 and 4, the patches being of such strong yet flexible material as not to tear but be lifted up where necessary to double over and permit the tucking in of an adjacent edge portion of a blank flap, this last being best shown in Figure 2.

After the patches have been located as described, the blank with its patches may be waxed as described in Letters Patent No. 110 1,365,250 granted to me January 11, 1921. However if the blank is treated as described

in my application filed concurrently herewith, Serial No. 497,885, the patches may be stuck thereto and the blank will then require no later waxing.

When the blank is folded, the corner patches first detach themselves in one location, each, and start to fold as indicated in Figure 3 which is an inside view of a portion of the blank which is to constitute one corner of the completed receptacle. Further folding of the blank causes the corner patches to assume the condition indicated in Figure 4 which is an outside view of the same corner as in Figure 3. Upon completion of the folding the patches are compactly folded and confined as indicated in Figure 2.

It will now be understood that I have provided a foldable blank with reinforcing members at those portions through or past which liquid is liable to force its way when the blank is converted to receptacle form and filled; also that the doubling or over-folding of the patches constitutes practically an automatic caulking of the seams at and close to the corners of the receptacle, which locations are always the ones where leakage is most likely to occur.

When the blank is folded, and assuming that a suitable adhesive has been applied to the proper portions thereof to hold it in folded condition for receiving liquid, it will be substantially as shown in Figure 5, with the flaps 17 inside the flaps 16, the flaps 13 extending up outside the flaps 16, and the upper or top-closing members standing straight up, with the wings 22 extending inside the flaps 21 and holding the latter steadily apart so that the receptacle can either be readily nested into another for storage or shipment, or can be conveniently filled. And the box presents a smooth interior, having no upper edges of any portions inside the box to interfere with nesting or to permit liquid to pass in behind such edges when being filled.

After the receptacle has been filled, the flap 18 is closed in, carrying the extension 19 with it. At the same time the wings 22 slide down inside the flaps 17 until the abrupt shoulders *z* of said wings contact with the inner face of the wall 14, thereby stopping further movement of the flap 18 below a horizontal position and preventing a splashing of the milk or other liquid. This also results in holding the flap 18 in position to have the flap 20 folded snugly onto it. After the flap 20 is folded down onto the flap 18, doubling the extension lip 19 over, the top cover flaps 21 are folded toward each other and may be connected by a sealing strip 23 as indicated in Figure 2.

The wings 22 serve another purpose. When a filled and closed box is to be opened, the sealing strip, if one has been employed, is broken and the upper portions then

opened to the positions indicated in Figure 5. The flap 18, with its side wings 22, then serves as a spout for directing liquid being poured from the box. To aid this spout function, the blank, prior to its being folded, is formed with a crease *y* extending longitudinally of the flap 18 and its extension 19. This causes the said flap and its extension to have a natural tendency to curve or bend outwardly as indicated in Figure 5, and this curvature strengthens the spout so that it will not be bent by the weight of liquid being poured out over it.

I do not limit myself to containers for liquids as containers of the character herein described and claimed may be used for other substances, and to exclude access of moisture or dust or germs to the contents of the container.

I have hereinbefore referred to two ways in which the container may be rendered waterproof by waxing the blank, and I will now describe a preferable and, so far as I am aware, novel method of attaining this result. The object of this feature of my invention which I am about to describe is to furnish paper vessels which have completely waxed (waterproofed) inner walls and the outer surfaces of which are entirely free of wax or other waterproofing material. To attain this object, each blank is waxed on one surface only over those areas which comprise the sections or flap portions indicated in Figure 1 at 12, 14, 15, 17, 18, 19, 20 and 21, leaving entirely uncoated the surfaces of the portions 13 and 16. This may be effected by running the blanks through a machine in the direction of the arrow *a*, the machine having a roll or other means for applying a coating to the upper surface (or to the under surface, according to whether the blank passes under or over the applying means) of the areas 20, 15, 12, 14, 18 and 19. Then the blank will be passed in the direction of the arrow *b* to be coated over the areas 17 and 21. This treatment leaves the other surface of the entire blank un-coated and therefore, since the portions 13, 16, are not coated on either surface, the adhesive employed to secure the parts in the folded or set up condition shown in Figure 2 does not have its action interfered with by the presence of wax between the parts which are required to stick together. This treatment however results in water-repellent material being carried by all those surfaces which are to be exposed to the contents of the receptacle when the blank is folded to the condition shown in Figures 2 and 5, the outer surfaces of the receptacle being entirely un-coated.

There are several advantages resulting from this method of treating and folding the blanks, one being that a lesser amount of paraffine or other coating material is

used than when both surfaces of the blank are coated partially or wholly, another being that printed matter can be applied anywhere on the un-coated surfaces of the blanks either before or after the treatment described, thereby enabling clearer reading matter to be exhibited on the outside of the receptacles than when printed surfaces also carry paraffine. Another advantage is that the coating can be effected simply and rapidly and accurately.

So far as this last described feature of my invention is concerned, I do not limit myself to the employment also of the reinforcing patches *x*, because there are many uses for paper boxes having waxed inner surfaces and un-waxed outer surfaces which do not require that the corners of the boxes shall be reenforced.

Having now described my invention, I claim:

1. An angularly creased blank having reinforcing patches extending across the intersecting creases which define the corners when the blank is folded to container form.
2. A water-proofed blank for a paper container having reinforcing patches at those portions which form the corners of the container.
3. A water-proofed paper receptacle having caulking material at those portions which form the bottom corners of the receptacle.

4. A container comprising an angularly folded paper blank provided with an internal layer of leak-stopping material at each of its top and bottom corners. 35

5. The method of producing a blank for a water-proof paper receptacle, consisting in applying a water-repellent material progressively in one direction to a portion of one surface of the blank and then applying water-repellent material progressively in another direction to a predetermined portion of the same surface of the blank, whereby one surface is partially coated and the other surface is left entirely uncoated. 40 45

6. The method of making a water-proof receptacle, consisting in first applying a water-repellent material progressively in one direction to a portion of one surface of a blank, then applying water-repellent material progressively in another direction to a predetermined portion of the same surface of the blank, leaving one surface partially coated and the other surface entirely uncoated, and then folding the blank to receptacle form and adhesively securing uncoated surface portions of the blank together. 50 55 60

In testimony whereof I have affixed my signature.

ELIE W. LABOMBARDE.
